CASING FOR AN AEROSOL DISPENSER

George Robert Boller, Robert F. Armstrong, and James W. Russell, New Canaan, Conn., assignors to Products International, Inc., New Canaan, Conn., a corporation of Delaware

Filed Jan. 27, 1964, Ser. No. 78,386

Term of patent 14 years

(Cl. D16—2)

Fig. 1

Fig. 3

Fig. 2

FIG. 1 is a perspective view of a casing for an aerosol dispenser.

FIG. 2 is a front elevational view of the casing.

FIG. 3 is a side elevation thereof, the opposite side being a mirror image of the side shown.

The undisclosed bottom portion of the casing is substantially flat and unornamented and the ornamentation disclosed on the front portion of the casing is understood to continue uniformly throughout the front panel members as indicated in FIGS. 1 and 2.

We claim:

The ornamental design for a casing for an aerosol dispenser, as shown and described.
